Inventor:

Mathias Dochnal,
By *Frank J. Haran*,
Attorney.

UNITED STATES PATENT OFFICE.

MATHIAS DOCHNAL, OF ST. LOUIS, MISSOURI.

BURIAL VAULT.

Application filed October 9, 1919. Serial No. 329,529.

To all whom it may concern:

Be it known that I, MATHIAS DOCHNAL, a citizen of the United States, residing in the city of St. Louis and State of Missouri, have 5 invented certain new and useful Improvements in Burial Vaults, of which the following is a specification.

My invention relates to burial vaults and has for its object to provide a concrete vault, 10 so constructed, as to be air and moisture proof when the cover section has been applied to the casket receiving section.

A further object of the invention is to provide what may be termed a self-locking 15 cover section wherein the cover section is held to the casket receiving section by resilient locking means.

A still further object of the invention is to provide the cover section with an annular groove to receive the upper edge of the 20 side wall of the casket receiving section.

With the above and other objects in view, the invention consists in certain novel features of construction, arrangement and combination of parts as will be fully described 25 in the following specification and finally pointed out in the claims hereto appended.

Referring to the accompanying drawings forming a part of this specification where- 30 in like characters of reference denote similar parts throughout the several views:

Fig. 1, is a perspective view of the casket receiving section of my improved burial vault.

Fig. 2, is a perspective view of the cover section.

Fig. 3, is a transverse sectional elevation of the upper portion of the vault with cover applied and clearly showing the self-locking 40 means.

Fig. 4, is a detail showing the cover section being lowered and about to engage the self-locking devices.

In carrying out the aim of my invention, 45 the vault comprises two sections, a casket receiving section designated A and a cover section B. These two sections A and B are preferably made of some approved form of reinforced concrete to render the vault wa- 50 terproof.

The casket receiving section A, consists of the bottom 1, the side walls 2 and the end walls 3. The side walls 2 and end walls 3 are provided a suitable distance below their 55 upper edges with a suitable outwardly ex- tending flange 4. The outer face of that

portion of the side and end walls extending upwardly from the flange 4 is inclined or beveled, as at 5, as clearly shown in Fig. 1. Each of the side walls 2 is provided with a suitable pocket, or recess 6, the open ends of which communicate with the inclined faces 5. A pair of suitable spring locking tongues 7 are suitably anchored, as at 8, to the side walls of section 1. The upper end of each locking tongue 7 is provided with a shoulder 9 and an inclined outer face 10. The free end of the tongues 7, when depressed, are receivable in the pockets 6, as is manifest.

The cover section B consists of the top portion 11 having the continuous depend- 70 ing tongue or wall 12 having an inclined or beveled inner face 13.

The under face of the top 11, of cover section B, is provided with an annular groove 14 to receive the upper end of the side and end walls of the casket receiving section B when the cover section is positioned upon the casket receiving section, as 75 clearly shown in Figs. 3 and 5.

The inner face 13 of each side wall 12 of the cover section B is provided with a pocket or recess 15 to form a lower shoulder 16, for engagement with the shoulder 9 of each locking tongue 7 when the cover section is positioned, as clearly shown in Fig. 3. The side walls 12, of the cover section B, are also each provided with a suitable screw member 17, which may be turned for re- 80 leasing each of the locking tongues 7 from engagement with the shoulder 16 when it is desired to remove the cover for any cause. The end of the screws are each protected by means of a dummy head, or plug 18 90 which must be removed before the screws can be turned with a screw driver. The screws and plugs are preferably carried in a suitable tubular member 19.

It is evident that in positioning the cover section B upon the casket receiving section A, that the inclined inner faces of the side walls 12 of the cover section will engage the inclined faces 10 of the locking tongues 7 forcing the tongues 7 into the openings 6 100 as the cover is lowered. When the cover has reached its closed position, it will be observed that the upper end of the end and side walls of the casket receiving section will seat in the annular groove 14 of the 105 cover section, and, that the shoulders 9 of the locking tongues 7 will rebound and en-

gage the shoulders 16 of the openings 15 of the cover section, thereby automatically locking the cover section to the casket receiving section.

5 When the cover B is positioned the vault is air and moisture proof as a wedge tight connection is formed between the side and end walls of the casket receiving section and the depending wall 12 of the cover section.

10 It will here be observed that the spring or automatic locking means is completely concealed when the cover section B has been positioned upon the lower section A.

15 The many advantages of the herein-described invention will readily suggest themselves to those skilled in the art to which it appertains.

20 I do not wish to be understood as having limited myself to the details of construction shown and described, but desire to have it understood that the vault structure I have shown in the drawings is merely illustrative, as it is manifest that various minor changes 25 may be made in the exact construction and particular arrangement of parts without departing from the spirit of my invention, hence reserve the right to make any such changes or modifications as may fairly fall 30 within the scope of the appended claims when fairly construed.

What I claim is:

35 1. A burial vault comprising a casket receiving section having an external annular flange positioned a suitable distance below the top edge of the walls of the casket receiving section, upwardly extending spring catches anchored in the flange of said casket receiving section, a shoulder formed near 40 the upper end of each spring catch terminating upwardly in a head having an inclined outer face, a cover section telescopically embracing the body of the casket receiving section above the annular flange, 45 said casket receiving section being provided with an internal recess opposite each spring catch and said cover section being provided

with a plurality of recesses to form locking shoulders for engagement with the shoulders of the spring catches when the cover section is positioned, a screw threaded member communicating with each cover section recess capable of releasing each spring catch shoulder with the lower shoulder of the cover recesses when the screw threaded members are moved inwardly thereby permitting the removal of the cover section from the casket receiving section.

50 2. A burial vault comprising a casket receiving section having a flange extending outwardly from the end and side walls a suitable distance below the top edges of the end and side walls, said walls having their outer faces beveled above said flange, a cover section having a continuous depending wall having inclined inner faces to engage the inclined outer faces of the end and side walls of the casket receiving section when the cover section has been positioned 55 on the casket receiving section, a plurality of spring catches anchored in the annular flange of the casket receiving section and each flange extending upwardly therefrom opposite a recess formed in the walls of the casket receiving section, a head formed at 60 the upper free end of each spring catch having an outer beveled face for engagement with the beveled inner face of the depending wall of the cover section when the cover section is being positioned upon the 65 casket receiving section, said cover section being provided with a spring catch receiving recess for each spring catch, and a screw threaded spring catch releasing member communicating with each cover recess, said member being capable of movement inwardly to release the spring catches from locking 70 engagement with the cover recesses to permit the cover section to be removed from the casket receiving section after having been once positioned thereon.

75 In testimony whereof, I have hereunto signed my name to the specification.

MATHIAS DOCHNAT.
